UNITED STATES PATENT OFFICE.

ROSE THAMM, OF BERKELEY, CALIFORNIA.

DESIGN FOR A LANTERN.

44,598.

Specification for Design.

Patented Aug. 26, 1913.

Application filed May 29, 1913. Serial No. 770,758. Term of patent 3½ years.

To all whom it may concern:

Be it known that I, ROSE THAMM, a citizen of the United States, residing at Berkeley, in the county of Alameda and State of California, have invented a new, original, and ornamental Design for a Lantern, of which the following is a specification, reference being had to the accompanying drawing, forming part thereof.

The figure is a vertical view of a lantern, showing my new design.

I claim:

The ornamental design for a lantern, as shown.

ROSE THAMM,

Witnesses:

MARION C. BHENEN,
H. A. SMITH.
